DESIGN FOR A PERCOLATOR TOP

Richard F. Krause, Massillon, Ohio, assignor to
The Enterprise Aluminum Company, Massillon,
Ohio, a corporation of Ohio

Application October 2, 1946, Serial No. 133,701

Term of patent 7 years

(Cl. D44—26)

To all whom it may concern:

Be it known that I, Richard F. Krause, a citizen of the United States, residing at Massillon, in the county of Stark and State of Ohio, have invented a new, original, and ornamental Design for Percolator Top, of which the following is a specification, reference being had to the accompanying drawing, forming part thereof.

Figure 1 is a top plan view of a percolator top, showing my new design;

Fig. 2 is a side elevation of the percolator top shown in Fig. 1;

Fig. 3 is a bottom plan view of the percolator top shown in Figs. 1 and 2; and,

Fig. 4 is a vertical sectional view through the percolator top shown in Figs. 1, 2 and 3.

I claim:

The ornamental design for a percolator top, substantially as shown.

RICHARD F. KRAUSE.
